UNITED STATES PATENT OFFICE.

ROBERT CUMMING ANNAND, OF SOUTH SHIELDS, ENGLAND.

APPARATUS FOR THE MANUFACTURE OF CURVED STEREOTYPE-PLATES.

1,117,151.

Specification of Letters Patent. Patented Nov. 17, 1914.

Application filed June 11, 1913. Serial No. 773,144.

To all whom it may concern:

Be it known that I, ROBERT CUMMING ANNAND, of Cornwallis street, South Shields, in the county of Durham, England, have invented certain new and useful Improvements in Apparatus for the Manufacture of Curved Stereotype-Plates, of which the following is a specification.

This invention relates to apparatus or machines for the manufacture of curved stereotype plates, wherein a collapsible core is employed which is expanded to the required circular form previous to the casting of the plate from a matrix secured in a curved casting back and is afterward collapsed or bent inward together with the cast plate, to enable the curved plate to be stripped by the core from the matrix without injury to the latter.

10 The invention relates more particularly to curved stereotype plate making machines of the type described in the specification of previous United States Letters Patent granted to me No. 887,373 dated 12 May 1908, namely, 15 wherein the plates are cast with the aid of such a core in a curved casting back which reciprocates together with a boring shell into positions in which the casting back and boring shell are alternately in position opposite to the core which is collapsed and operated to bend the plate slightly, strip it from the matrix and raise it out of the casting back, and then descends and deposits the plate in the boring shell when this has moved into 20 position opposite the core, the boring shell then carrying the plate to mechanism for boring or boring and finishing the same while the casting back returns to position for coöperation with the core to cast another 25 plate.

According to the present invention, instead of making the collapsible core of separate plates hinged together, I construct it as a continuous or non-hinged element possessing sufficient resiliency to permit of the small amount of flexing required for bending the cast plate inward and stripping it from the matrix. I also provide improved means for cooling this core, by arranging 30 for water or cooling liquid to flow through the hollow interior of a member carried by or attached to the top of the core proper and forming the front of the pouring gate, and also through a narrow space or chamber provided between the resilient core and an inner 35 wall or backing arranged to flex therewith in

the bending operation. The cooling liquid is preferably admitted at one end of the member forming the front of the pouring gate (hereinafter called the "gate front") 60 and led from the other end thereof to a channel extending across the inner face of the core and opening into top of the space between the core and backing, so that it spreads through the space between same and is led 65 off at the bottom of this space.

According to a further part of the invention the collapsing of the resilient core is effected by means of rocking levers pivotally connected to the core at suitable points near 70 the top and bottom and actuated by a cam on the cam shaft of the machine through the medium of links or members connected to said rocking levers and to a shaft rocked by a lever actuated by the said cam, the said 75 rocking levers and rocking shaft being mounted in the rocking frames that serve for moving the core into and out of the casting back.

The accompanying drawings represent by 80 way of example the application of the improvements of the present invention to a machine of the general character described in my said prior Patent No. 887,373, only so much of the machine being shown as is necessary to enable the invention to be understood.

Figure 1 is a plan of the casting back and core with the mechanism for expanding and collapsing the core. Fig. 2 is a corresponding end view. Fig. 3 is a section through 90 the casting back and core. Fig. 4 is a detail end view of the casting back and matrix clamping means. Fig. 5 is a plan view thereof. Fig. 6 is a fragmentary view looking along the arrow A Fig. 5. Fig. 7 is a 95 diagrammatic view of the cam mechanism for controlling the movements of the stopper bar that closes the bottom of the casting mold.

The core proper consists of a curved plate 100 1 of steel, say about $\frac{3}{8}$ " thick and of sufficient extent circumferentially to enable the core to be fixed conveniently. Inside the plate 1 a lining plate 2 of steel or brass is fitted so as to leave a narrow space 3, say $\frac{1}{4}$ " in 105 width, for the flow of cooling water between the two plates.

The top and bottom edges of the lining plate 2 are flanged up at $2^{\circ} 2^{\circ}$ to abut against hollow castings 4, 4, extending along the 110 core and formed with water channels 4¹, 4², and the water space 3, which communicates

with the channels 4^a 4^a for the length of the core, is closed at top, bottom and sides by packing material 26 (e. g. engine packing) fitted between the plates 1 and 2, the whole 5 being secured firmly together in a watertight manner by means of bolts and nuts 5 at intervals all around the top, bottom and sides.

On top of the core is bolted or otherwise 10 fixed a casting 6 forming the pouring gate front and containing a channel 7 extending for the length of the pouring gate 7^a. A flexible pipe 8 admits cooling water to one end of the channel 7. From the other end 15 of the channel 7 the water passes by a flexible pipe 8^a to the top channel 4^a inside the core. The cooling water thus spreads through the shallow water space 3 and into the bottom channel 4^a from which it passes 20 away by a pipe 10. The pipe 8^a may conveniently admit the water to the top channel 4^a at a point toward the middle of the length of the core.

The back of the pouring gate is likewise 25 cooled by a current of water supplied to the hollow gate back 11 which in the example shown likewise forms the clamping gripper for the top of the matrix secured in the casting back, and for this purpose is arranged 30 to pivot on trunnions 12 in the top of the casting back 13. The casting back 13 reciprocates together with the boring shell (not shown) on a slide 14 in the manner described in my said previous patent, as will 35 be understood without further explanation.

15 represents the bottom gripper for clamping the lower edge of the matrix in the casting box, and the sides of the matrix are also clamped by loose side gages in the 40 manner described in my said previous patent. Figs. 4, 5 and 6 illustrate such means for clamping the matrix. 150, 150 are the loose side gages disposed in the casting back 13, these being adapted to overlap 45 the matrix at the sides and being inserted in the back 13 by a semi-circular feather 151 with which they are each formed, said feathers fitting in grooves in the shell and preventing the side gages from 50 slipping out when released. The top and bottom edges of the matrix are clamped by the rocking grippers 11 and 15 mounted respectively on the spindles 12 and 152 controlled by hand levers 12^a and 152^a capable 55 of being locked in the matrix clamping position by spring plungers 12^b 152^b adapted to engage in suitably positioned holes in the back 13. The top gripper 11 also serves 60 to clamp the side gages 150 and hence the side edges of the matrix in position, by means of a projecting edge 153 of the same thickness as the matrix, formed on the upper edge of each side gage and which 65 therefore abuts against the top gripper when this is turned to clamping position. The

lower ends of the grooves in the back 13 for the feathers 151 are undercut as indicated at 154 and the feathers are shaped to correspond, and by this means, together with the gripping of the projecting edges 153 the 70 side gages are prevented from springing in with the cast plate when the core is collapsed.

16 is a stopper bar for closing the casting space 27 during the casting operation. 75 The bar 16 also acts against the lower edge of the cast plate to strip the plate from the core into the boring shell when the boring shell comes opposite to the core, this stopper bar being rocked into and out of its operative 80 positions by cam gear in a manner similar to that described in my said previous patent, by cam gear illustrated in Fig. 7, which shows one of the pair of cams, forked levers and rocking arms whereby this motion is 85 imparted to the stopper bar. The stopper bar 16 is secured to the pair of rocking arms 155 to which are linked forked levers 156 the forks of which slide on the cam shaft 157 of the machine. The levers 156 carry 90 rollers 156^a working in the grooves 158 of the cams 159 on the cam shaft 157. Fig. 7 shows only one of the said cams, forked levers and rocking arms, it being understood 95 that there is a pair of each of these mounted parallel to each other.

17, 17 are two frames mounted to rock about stud shafts 18 carried in the machine framing, for the purpose of swinging the core into and out of the casting box and 100 boring bed at the required time. These rocking levers are actuated by means of suitable cams (not shown) in a manner similar to that described in the previous specification.

28, 28 are upper and lower rocking levers mounted on studs 29, 29 in the rocking frames 17, 17 at each side of the core, and pivotally connected at their inner ends to the core as at 30, 30 at suitable points to 110 enable the core to be properly collapsed and expanded. At their outer ends the rocking levers 28, 28, are connected to links 19, 19 pivoted between the flanges of collars 20, 20 keyed by feathers 21, 21 on a transverse 115 shaft 22 mounted in the rocking frames 17, 17.

On the shaft 22 is keyed a lever 23 carrying a cam roller 24 working in the groove 25^a of a cam 25 serving for collapsing and expanding the core and mounted on the cam 120 shaft 31 of the machine.

The cycle of operation of the machine illustrated is similar to that described in the specification of the previous patent and it is therefore not necessary to describe it fully in detail. Assuming a plate to have been cast between the expanded core and the casting back 13 and to have cooled sufficiently, the machine is started. When the V portion 125 130

of the cam groove 25^a reaches the cam roller 24 the lever 23 is rocked outward and thus through the links 19 and levers 28 flexes the core slightly inward, together with the cast plate (which is connected to the core by ribs cast on the inner face of the plate as explained in the previous specification). The plate can thus be stripped from the matrix without injury to the latter. The frames 17, 17 now rock outward with the core and plate under the action of their controlling cams and thus strip the plate from the matrix in the casting back 18, which slides away so that the boring shell comes into position opposite the core, the frame 17 rocking in again and depositing the cast plate in the boring shell. During this interval the core and plate still remain partially collapsed, in consequence of the combined effect on the rocking motion of the frames about the shaft 18 and of the contour of the cam groove 25^a. This is desirable in order to prevent damage to the bottom and top edges of the plate when same is swung into the boring shell. The plate having been stripped from the core into the boring shell, the frames 17, 17 rock out again under the action of their cams and the casting back 18 returns to position opposite the core, which rocks forward with the frames 17, 17 into position in the casting back and in doing so expands to circular form for the next casting operation. The next supply of metal to form a plate is then pumped into the pouring gate and the machine stops. Meanwhile the boring shell has carried the previously cast plate to the boring, finishing and delivery mechanism. When the new plate has cooled sufficiently the machine is restarted and the cycle is repeated.

With the machine described and illustrated it is preferred not to break off the jet from the plate by means of a sliding member on the core, as described in the previous specification, but to break off the jet subsequently after the boring shell has carried the cast plate to the position for the finishing operations. This, however, forms no part of the present invention.

It will be understood that the particular form of apparatus described and illustrated is given by way of example and can be varied in its details without departing from the spirit of the invention.

What I claim and desire to secure by Letters Patent is:—

1. Apparatus for the manufacture of curved stereotype plates comprising a continuous non-hinged collapsible core capable of inward flexion, a casting box for co-operation with said core to cast the plates, means for fixing a matrix in said casting box, and means for flexing the non-hinged core inward with the cast plate and for expanding the non-hinged core to casting shape,

shape, substantially as and for the purpose described.

2. Apparatus for the manufacture of curved stereotype plates comprising a continuous non-hinged collapsible core capable of inward flexion, a casting box for co-operation with said core to cast the plates, means for fixing a matrix in said casting box, and means for flexing the non-hinged core inward with the cast plate and for expanding the non-hinged core to casting shape, and means for cooling the cast plate on the core by a current of cooling liquid applied to the inner face of the continuous flexible core, substantially as described.

3. Apparatus for the manufacture of curved stereotype plates comprising a continuous non-hinged collapsible core capable of inward flexion, a casting box for co-operation with said core to cast the plates, means for fixing a matrix in said casting box, and means for flexing the non-hinged core inward with the cast plate and for expanding the non-hinged core to casting shape, means for cooling the cast plate on the core by a current of cooling liquid applied to the inner face of the continuous flexible core and to the wall of the pouring space, substantially as described.

4. Apparatus for the manufacture of curved stereotype plates comprising a continuous non-hinged collapsible core capable of inward flexion, a casting box for co-operation with said core to cast the plates, means for fixing a matrix in said casting box, and means for flexing the non-hinged core inward with the cast plate and for expanding the non-hinged core to casting shape, a flexible inner backing to the core, spaced apart therefrom to form a narrow liquid chamber between the core and backing, and means for supplying cooling liquid to said liquid chamber, substantially as described.

5. Apparatus for the manufacture of curved stereotype plates comprising a continuous non-hinged collapsible core capable of inward flexion, a casting box for co-operation with said core to cast the plates, means for fixing a matrix in said casting box, and means for flexing the non-hinged core inward with the cast plate and for expanding the non-hinged core to casting shape, a hollow front gate member extending across the core, a flexible inner backing to the core, spaced apart therefrom to form a narrow cooling chamber between core and backing, and means for supplying cooling liquid to said hollow front gate member and said narrow liquid chamber, substantially as described.

6. Apparatus for the manufacture of curved stereotype plates comprising a continuous non-hinged collapsible core capable of inward flexion, a casting box for co-operation with said core to cast the plates, means

for fixing a matrix in said casting box, and means for flexing the non-hinged core inward with the cast plate and for expanding the non-hinged core to casting shape, a hollow front gate member extending across the core, a flexible inner backing to the core, spaced apart therefrom to form a narrow cooling chamber between core and backing, means for admitting cooling liquid at one end of said front gate member, a flexible liquid connection between the opposite end of the front gate member and the said narrow cooling chamber, and means for leading off the liquid from said narrow cooling chamber, substantially as described.

7. Apparatus for the manufacture of curved stereotype plates comprising a continuous non-hinged collapsible core capable of inward flexion, a casting box for cooperation with said core to cast the plates, means for fixing a matrix in said casting box, and means for flexing the non-hinged core inward with the cast plate and for expanding the non-hinged core to casting shape, a hollow front gate member extending across the core, a flexible inner backing to the core, spaced apart therefrom to form a narrow cooling chamber between core and backing, a flexible liquid connection between said hollow front gate member and said cooling chamber, whereby the cooling liquid is led from the front gate member to said cooling chamber, and means for leading off the liquid from said cooling chamber, substantially as described.

8. Apparatus for the manufacture of curved stereotype plates comprising a continuous non-hinged collapsible core capable of inward flexion, a casting box for cooperation with said core to cast the plates, means for fixing a matrix in said casting box, and means for flexing the non-hinged core inward with the cast plate and for expanding

the non-hinged core to casting shape, a hollow front gate member extending across the core, a flexible inner backing to the core, spaced apart therefrom to form a narrow cooling chamber between core and backing, means for admitting cooling liquid at one end of said front gate member, a flexible liquid connection between the opposite end of the front gate member and the said narrow cooling chamber, and means for leading off the liquid from said narrow cooling chamber, substantially as described.

9. Apparatus for the manufacture of curved stereotype plates comprising a continuous non-hinged collapsible core capable of inward flexion, a casting box for cooperation with said core to cast the plates, means for fixing a matrix in said casting box, and mechanism for collapsing and expanding the core and moving the same into and out of the casting box, said mechanism comprising rocking levers (28, 28) pivoted to the core near the top and bottom thereof, rocking frames (17) for moving the core into and out of the casting box, a rocking shaft (22) mounted in said rocking frames, links (19, 19) connected to said rocking levers (28, 28) and to said rocking shaft, a cam lever (23) on said rocking shaft, and a cam (25) for operating said rocking levers (28, 28) through said cam lever, rocking shaft and links to expand and collapse the core, substantially as described.

In witness whereof, I have hereunto signed my name in the presence of two subscribing witnesses.

ROBERT CUMMING ANNAND.
